UNITED STATES PATENT OFFICE.

ALBERT F. PRIBNOW, OF MELLEN, WISCONSIN.

ELECTRIC-INCANDESCENT-LAMP CARRIER.

1,077,751.

Specification of Letters Patent.

Patented Nov. 4, 1913.

Application filed March 19, 1913. Serial No. 755,461.

To all whom it may concern:

Be it known that I, ALBERT F. PRIBNOW, a citizen of the United States, residing at Mellen, in the county of Ashland and State of Wisconsin, have invented a new and useful Electric-Incandescent-Lamp Carrier, of which the following is a specification.

The present invention appertains to a carrier or holder for incandescent electric lamps and aims to provide a novel and improved article of this character.

It is the object of the present invention to provide a carrier for holding or containing an incandescent lamp in order that the lamp may be safely transported without danger of breakage, and without the liability of the lamp being dislodged.

Another object of the present invention is to provide a carrier or holder of the character indicated which may accommodate various styles of bulbs or globes with equal propriety and success.

A further object of the present invention is to provide a carrier or holder of the nature indicated, embodying a longitudinally corrugated tube or casing adapted to snugly receive the globe or bulb of the lamp, in connection with a novel and improved member secured within the tube or casing for the reception of the plug or screw end of the lamp so that the plug or screw end of the lamp may be maintained in position during transport.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:

Figure 1 is a plan view of the blank from which the plug-holding member is formed. Fig. 2 is a longitudinal section of the carrier or holder constructed in accordance with the present invention, and disclosing one form of lamp held thereby. Fig. 3 is a sectional view taken on the line 3-3 of Fig. 2, the lamp being removed. Fig. 4 is a longitudinal section of the carrier or

holder taken at right angles to the plane of section of Fig. 2, and showing another form of lamp or bulb held by the carrier.

In carrying out the invention, reference being had in detail to the drawing, there is provided a longitudinally corrugated tube or casing 5, the walls of which are adapted to yield so as to snugly receive the bulb or globe of the lamp, so that the globe or bulb may be protected from breakage in handling or transport. Within one end of the tube or casing 5, there is secured a member for embracing or engaging the plug or screw end of the lamp, this member embodying a blank 6 having the opposite reduced end tabs 7. The blank 6 fits diametrically within one end of the tube or casing 5, with the tabs 7 outturned and lying against the opposite walls of the casing. The blank 6 is hexagonal in contour, or has its intermediate portion enlarged with the tabs 7 forming extensions on opposite sides. The blank 6 is provided with a central opening 8 slightly smaller in diameter than the diameter of the plug or screw end of the lamp, and a series of short radial slits or cuts 9 are formed in the blank 6 around the opening 8 so as to provide a series or plurality of laterally flexible lips 10. The blank 6 is preferably fashioned from heavy paper or cardboard, although other materials may be employed with equal effect. The side edges of the flexible member 6 are spaced from the respective walls of the tube to permit the said walls and said member to vibrate with respect to each other in various directions. The tabs 7 may be secured to the walls of the casing or tube 5 in any desirable manner, as by means of staples or clips 11 engaging through the tabs 7 and casing, although an adhesive or other means may be employed.

It is evident from the foregoing that the casing 5 admits of the ready insertion of the lamp, and holds the globe or bulb in such a manner as to protect it from breakage in the handling or transportation of the lamp. In inserting the lamp, the plug or screw end is inserted into the end of the casing opposite the end containing the plug embracing member, and the lamp is then slid inwardly so as to force the plug through the opening 8. The plug of the lamp being forced through the opening 8, will cause the lips 10 to flex outwardly, it being noted that the opening 8 is smaller in diameter than the plug, so that the lips 10 will engage

the thread convolutions of the plug and will in this manner retain the plug against longitudinal and lateral movements.

It will be noted that although the lamp is held against displacement within the carrier or holder, the lamp may yield slightly in various directions, as the holder or carrier is shaken about. The present carrier is also adapted to receive various styles of lamps, such as a lamp embodying an elongated bulb as depicted in Fig. 2, and such as a lamp embodying the globe or short bulb as depicted in Fig. 4. In each case, the globes or bulbs are held effectively in position so as to assure against breakage and displacement. The lamp will thus be prevented from falling or slipping out of the casing 5 as the same is handled, although the lamp may be forcibly dislodged or removed without difficulty and without any injurious effect to the filament.

The present holder or carrier is comparatively inexpensive and simple, and is sufficiently so that it may be discarded after once being used, although the holder or carrier may be employed repeatedly, if desired. The present carrier or holder also permits the lamps to be compactly packed within a carton, shipping box or other container.

The lateral resiliency of the casing 5 will permit the bulb or globe to vibrate laterally in transport, and the member 6 will permit the bulb or globe to reciprocate or vibrate longitudinally, while the lips 10 will permit

the plug to vibrate laterally, so that any jar will not prove injurious to the lamp. As a whole, the carrier or holder is so constructed so as to successfully resist the various conditions to which the lamp is subjected in handling or transportation.

The present carrier, as above indicated, may be employed for various styles of globes or bulbs without the necessity of wadding or packing but it is to be understood, of course, that the carrier may be constructed in various sizes according to the various sizes of lamps.

Having thus described the invention, what is claimed as new is:—

An incandescent electric lamp carrier embodying a resilient tube, and a flexible member disposed diametrically within one end of the tube, the said member having reduced end tabs bent against and secured to opposite walls of the tube, the intermediate portion of the said member being enlarged and being provided with an opening to receive the plug of a lamp, and the side edges of the flexible member being spaced from the respective walls of the tube.

In testimony that I claim the foregoing as my own, I have hereto affixed my signature in the presence of two witnesses.

ALBERT F. PRIBNOW.

Witnesses:

T. A. HUMPHREY,
CATHERINE MABRE.
